[57]**CLAIM**

The ornamental designs for a scope ring, as shown and described.

DESCRIPTION

FIG. 1 is a perspective view of the scope ring showing my new design;

FIG. 2 is a front elevational view of the scope ring of FIG. 1 with the rear elevational view being an identical mirror image of the view of FIG. 2;

FIG. 3 is a top elevational view of the scope ring of FIG. 1; FIG. 4 is a right side elevational view of the scope ring of FIG. 1;

FIG. 5 is a left side elevational view of the scope ring of FIG. 5;

FIG. 6 is a bottom elevational view of the scope ring of FIG. 1;

FIG. 7 is a perspective view of a second embodiment with the top elevational view being that shown in FIG. 3;

FIG. 8 is a front elevational view of the scope ring of FIG. 7 with the rear elevational view being an identical mirror image of the view of FIG. 8;

FIG. 9 is a right side elevational view of the scope ring of FIG. 7;

FIG. 10 is a left side elevational view of the scope ring of FIG. 7; and,

FIG. 11 is a bottom elevational view of the scope ring of FIG. 7.

The broken line showing of a mounting base and sighting scope in FIGS. 1 and 7 is for illustrative purposes only and forms no part of the claimed design.
